(57) **CLAIM**

We claim the ornamental design for a brownie cutter, as shown and described.

DESCRIPTION

FIG. 1 is a perspective view of the brownie cutter;

FIG. 2 is a front side view of the design embodiment shown in FIG. 1;

FIG. 3 is a top view of the design embodiment shown in FIG. 1;

FIG. 4 is a bottom view of the design embodiment shown in FIG. 1; and,

FIG. 5 is a side view of the design embodiment shown in FIG. 1.

The subject matter shown in dashed lines, and any surfaces of the design not shown, including interior surfaces, form no part of the claimed invention.
